UNITED STATES PATENT OFFICE.

JAMES EDWARD BENNETT, OF MOMENCE, ILLINOIS.

BASE-BALL GLOVE.

SPECIFICATION forming part of Letters Patent No. 789,480, dated May 9, 1905.

Application filed December 17, 1904. Serial No. 237,242.

To all whom it may concern:

Be it known that I, JAMES EDWARD BENNETT, a resident of Momence, in the county of Kankakee and State of Illinois, have invented 5 certain new and useful Improvements in Base-Ball Gloves; and I do hereby declare the following to be a full, clear, and exact description of the invention, such as will enable others skilled in the art to which it appertains to 10 make and use the same.

My invention relates to improvements in base-ball gloves, and more particularly double and single gloves used in the game of base-ball, the object of the invention being to provide 15 improved gloves which will permit the ball to be caught and held in the glove or gloves and not merely serve as a stop for the ball, as is the case with heavy gloves or pads as are in common use.

With these and other objects in view the invention consists in certain novel features of construction and combinations and arrangements of parts, as will be more fully herein-after described, and pointed out in the claims. 20

In the accompanying drawings, Figure 1 is a perspective view illustrating my improved double glove in operation. Fig. 2 is a rear or back view of the glove. Figs. 3 and 4 are 25 views of modified forms of double glove. Figs.

5 and 6 are front and back views of a form of single glove, and Figs. 7 and 8 are similar views of a modified form of single glove.

In the construction of double gloves shown in Figs. 1 and 2 right and left hand heavy 35 gloves or pads are employed and connected around their rear or back edges by a sheet D, in which the ball strikes and draws the gloves together to tightly hold the ball, and an extra sheet or strip F is secured by stitching E to 40 the lower edge of sheet D and to the gloves or pads and prevents the ball dropping out, especially when the player removes his hand from one glove to grasp and throw the ball.

If the player is right-handed, the right-hand 45 glove or pad will have large fingers and thumb or be in mitten form to permit the easy and quick removal of that hand to grasp and throw the ball. If he be left-handed, the left-hand glove will be provided with this mitten or 50 loose glove, and I have shown at 1st fingers and thumb such as may be used.

In Fig. 3 a form of double glove is shown in which the connecting-sheet D or receptacle which is formed thereby projects considerably to the rear or back of the gloves or pads. 55

In Fig. 4 the double glove is made up of outer and inner sheets of leather, having an open mouth to receive the ball and provided with hinges 4^a, inclosed and held in place by stitching, which compels the sections at sides 60 of the open mouth to come together or be closed by the ball entering the glove. Suitable padding may be provided between the outer and inner sheets of the double glove, and finger-receptacles 1^a are provided on the out- 65 side of the sections or halves of the glove.

In Figs. 5 and 6 I illustrate a single glove or pad in which the glove, between the thumb portion and finger portion of the glove and at the opposite edge of the glove, as shown at 70 2 and 3, is indented and lacing is provided to give the glove the proper shape. In the front of the glove, around the finger edge, raised padding 5 is located, and similar raised padding 4 is located around the upper portion of the 75 glove, which forms a receptacle for the ball in the palm portion of the glove, and the notched sides of the glove permit the same to fold to grasp and hold the ball.

In the form shown in Figs. 7 and 8 the glove 80 is slit at its back both horizontally and vertically and the glove or hand-receptacle secured to the back and laced longitudinally and vertically to give the glove proper shape, and this glove is also padded around its edge to 85 form a hollow for the ball and can be adjusted or folded by the hand to grasp the ball.

With all of my improved forms of glove it will be seen that the ball can be held in the glove, which is a great improvement on the 90 forms of glove or pad in use, which only serve as stops for the ball and must be grasped and held by the free hand to prevent falling from the glove or pad.

Various other slight changes might be made 95 in the general form and arrangement of the parts described without departing from my invention, and hence I do not restrict myself to the precise details set forth, but consider myself at liberty to make such slight changes 100 and alterations as fairly fall within the spirit and scope of my invention.

Having fully described my invention, what I claim as new, and desire to secure by Letters Patent, is—

1. A base-ball glove constructed to provide a pocket for the ball and having means to allow the closing of the pocket on a ball to permit the latter to be held in the glove.
2. A base-ball glove or pad constructed to form a pocket or receptacle for the ball and having separated portions to permit the glove to be folded by the hand to grasp the ball.
3. A base-ball glove, comprising gloves or fingers for each hand and a sheet connecting them.
4. The combination with a glove for each hand and a sheet secured to the edges of both gloves and forming a receptacle for the ball between them.
5. The combination with a glove for each

hand, one glove constructed to permit easy and quick removal of the hand therefrom, and a sheet secured to both gloves and forming a receptacle for the ball between the gloves.

6. The combination with a trough or receptacle for the ball and devices for the hands at both sides thereof.

7. As a new article of manufacture, a double glove for use in the game of base-ball constructed for the reception of both hands of the player at the same time.

In testimony whereof I have signed this specification in the presence of two subscribing witnesses.

JAMES EDWARD BENNETT.
